FLUID DISPENSING SYSTEM

Harry C. Grant, Jr., New York, N. Y., assignor to
 Specialties Development Corporation, Bloom-
 field, N. J., a corporation of New Jersey

Application August 27, 1941, Serial No. 408,409

9 Claims. (Cl. 222—3)

The present invention relates to high pressure fluid medium dispensing systems, and more particularly, to apparatus employed in releasing and distributing liquefied carbon dioxide gas stored under high pressure and commonly used for fire extinguishing purposes.

Fire extinguishing systems of this type generally comprise a battery of storage containers for the high pressure fluid, distribution piping for the released fluid, and suitable apparatus associated with the containers for the manual or automatic release of the fluid into the distribution piping.

This invention is more specifically concerned with an improved fluid releasing apparatus of the type referred to.

In the past, mechanical, pneumatic and electrical methods have been used to initiate the release of the stored fluid. While the choice of these methods was largely determined by the circumstances prevailing in the particular application, the pneumatic method has had a fairly general acceptance because of the fact that the fluid to be released presents a convenient source of pneumatic energy.

The present method provides for the utilization of a portion of the stored fluid pressure medium to operate a pressure operable fluid releasing mechanism of the system. This calls for the use of special operating fluid containers or the introduction of some of the fluid released into the distributing conduits for operating the releasing mechanism.

An object of the present invention is to provide an improved fluid pressure operated fluid dispensing system as embodied in a fire extinguishing apparatus of the type referred to.

Another object of the invention is to provide a system of the type described which utilizes the pressure of the fluid stored to operate its own releasing mechanism.

Another object is to provide a releasing mechanism for use with a high pressure fluid container, in which a small initially released portion of the stored fluid from the container is utilized to cause the operation of the main releasing mechanism of the container.

Another object is to provide a releasing mechanism as described, the operation of which by the pressure of the stored fluid may be initiated by a relatively small initial controlling force.

A further object is to provide a distribution system wherein the simultaneous release of all storage containers or the separate release of each container is possible.

Other and further objects of the invention will be obvious upon an understanding of the illustrative embodiment about to be described, or will be indicated in the appended claims, and various advantages not referred to herein will occur to one skilled in the art upon employment of the invention in practice.

A preferred embodiment of the invention has been chosen for purposes of illustration and description and is shown in the accompanying drawing, forming a part of the specification, wherein—

Figure 1 is a schematic view of a fluid medium distributing system illustrating an embodiment of the present invention, while

Figure 2 is a schematic view illustrating a modification thereof.

Referring now to the drawing, there are shown systems comprising a primary fluid storage reservoir, receptacle, or container 1 and secondary reservoirs, containers or receptacles 2, of which there may be one or more. All the containers are provided with fluid actuated fluid release control means 3 comprising retaining means such as a main valve 4 which controls the discharge of the fluid medium from containers 1 and 2 by way of a valve seat 5, a chamber 6 and discharge tubing 7. The tubing 1 may lead to a common discharge conduit 8, as shown, or to individual points of discharge as desired. The fluid actuated release control means 3 further comprise operating means such as a piston 9 adapted to operate the valve 4 and being reciprocally movable in a cylinder 10, which is separated from the chamber 6 by means of a partitioning wall 11. The piston 9 and the valve 4 are operatively joined by a connecting rod 12 which passes through an appropriate aperture in wall 11.

In Figure 1, the upper portions of cylinders 10 are inter-connected through communication tubing 13. A fluid supply connection 14 is provided for directly connecting the primary container 1 with the portion of its cylinder 10 in back of the piston 9. A control means or pilot valve 15 is located in the connection 14. This pilot valve 15 may be operated locally or remotely by means of any one of a variety of manual or automatic actuating means 16 as commonly employed in connection with fluid distribution apparatus of the type referred to. Such pilot valve actuating means is illustrated symbolically in the drawing as a manually operable knob, but details thereof form no part of the present invention.

Referring now to Figure 2, each of the containers is equipped with a supply connection 14 having a pilot valve 15 located therein and connecting the container with the portion of its cylinder 10 in back of the piston 9. However, instead of the cylinders 10 being directly connected with each other by tubing 13 as shown in Figure 1, the cylinder 10 of the primary container 1 is connected for causing the fluid pressure medium therein to effect operation of the pistons 9 of the secondary containers through tubing 17 connected to fluid operated actuating means 18 for the pilot valves 15 of the secondary containers or receptacles 2. In connection with the secondary containers 2, illustrated in Figure 2, the term "fluid actuated fluid release control means," also includes the pilot valve 15 and the fluid pressure actuated means 18 of the containers 2.

The fluid operated actuating means 18 comprises a cylinder 19 and a piston 20 movable therein, a connecting rod 21 joining piston 20 and the valve 15. Each of the pilot valves of the secondary containers also is individually manually operable by means 22 comprising a knob, capable, when actuated, of depressing the piston 20 to thereby open the valve 15. From the foregoing description, it will be understood that the pilot valve 15 of the primary container (Figures 1 and 2) may be remotely operable by an actuating means 18 as described in connection with the pilot valves of the secondary containers.

The operation of the system is as follows:

In the system shown in Figure 1, initial actuation of the pilot valve 15 of the primary container 1, permits fluid under pressure from this container to reach the cylinders 10, where the pressure acts to depress the pistons 9, thus opening the main valves 4 and causing the fluid medium of all of the containers or reservoirs to be discharged into the common discharge conduit 8.

In the case of the system of Figure 2, actuation of the pilot valve 15 of the primary container 1, permits fluid under pressure from the container to reach the cylinder 10, there to actuate the piston 9 and to open the main valve 4 as in Figure 1.

Here, however, the pressure fluid controlled by the pilot valve 15 of the primary container, instead of operating the pistons 9 and main valves 4 of the secondary containers, is made to actuate the pistons 20 of the pilot valve actuating means 18 of secondary containers 2. The pilot valves 15 of the secondary containers, in turn, permit the pressure fluid of each of the containers to operate their individual pistons 9 and main valves 4. In this system, it is also possible to cause the release of the fluid from each of the secondary containers separately, by an initial actuation of each individual knob 22. It will be seen, that this system is somewhat more flexible than that illustrated in Figure 1, in so far as any one of the secondary or all of the containers may be released in accordance with the prevailing needs.

It will be evident that the initial actuation of the primary container pilot valve may be accomplished, as already indicated, by remote or local control means which are operated by manual, mechanical, pneumatic or electrical apparatus, the details of which are not pertinent to this invention.

From the foregoing, it will be seen that this

invention provides fluid pressure medium distribution systems or the like in connection with a plurality of receptacles or containers, in which the pressure of the fluid within a container is utilized to effect the release of the main bulk of its own fluid.

Having described only a typical and preferred form of the invention, I do not wish to limit myself to the specific details set forth but wish to reserve to myself any changes or variations and the mechanical equivalents of the apparatus illustrated that may appear to those skilled in the art or fall within the scope of the following claims.

I claim:

1. In combination: a primary receptacle containing a fluid under pressure, a secondary receptacle containing a fluid under pressure, delivery means into which the fluid from said primary and said secondary receptacle is delivered when it is released, primary fluid retaining means for retaining the fluid in said primary receptacle, primary fluid actuated operating means for said primary retaining means to release the fluid retained thereby, a direct fluid flow connection between said primary operating means and said primary receptacle, primary pilot valve means for said fluid flow connection, actuating means for said primary pilot valve means, fluid actuated fluid release control means including retaining means for said secondary receptacle, and means forming a fluid flow connection between said fluid release control means for said secondary receptacle and said primary operating means, whereby said fluid release control means for said secondary receptacle is adapted to be actuated upon an initial actuation of said primary pilot valve means.

2. In combination: a primary receptacle containing a fluid under pressure, primary fluid retaining means for retaining said fluid in said receptacle, a secondary receptacle containing a fluid under pressure, secondary fluid retaining means for retaining said fluid in said secondary receptacle, delivery means into which the fluid from said primary and said secondary receptacle is delivered when it is released, primary fluid actuated operating means for said primary fluid retaining means to release the fluid from said primary receptacle, secondary fluid actuated operating means for said secondary fluid retaining means to release the fluid from said secondary receptacle, a direct fluid flow connection respectively between said primary operating means and said primary receptacle and a connection between said secondary operating means and said secondary receptacle, primary pilot valve means for said fluid flow connection to said primary operating means, actuating means for said primary pilot valve means, and fluid pressure operated secondary pilot valve means for said fluid flow connection to said secondary operating means, said last named pilot valve means being in fluid flow connection with said primary fluid actuated operating means and being adapted to be actuated by fluid from said primary receptacle upon actuation of said primary pilot valve means.

3. In combination: a primary receptacle containing a fluid under pressure, primary fluid retaining means for retaining said fluid in said receptacle, a secondary receptacle containing a fluid under pressure, secondary fluid retaining means for retaining said fluid in said secondary receptacle, delivery means into which the fluid

from said primary and said secondary receptacle is delivered when it is released, primary fluid actuated operating means for said primary retaining means to release the fluid from said primary receptacle, secondary fluid actuated operating means for said secondary retaining means to release the fluid from said secondary receptacle, a direct fluid flow connection between said primary operating means and said primary receptacle and a connection between said secondary operating means and said secondary receptacle, primary pilot valve means for said fluid flow connection to said primary operating means, actuating means for said primary pilot valve means including a manually operable member, and fluid pressure actuated secondary pilot valve means for said fluid flow connection to said secondary operating means, said secondary pilot valve means being in fluid flow connection with said primary fluid actuated operating means and being adapted to be actuated by fluid from said primary receptacle upon actuation of said primary pilot valve means.

4. For use in a fluid medium dispensing system, the combination: a first receptacle containing a fluid under pressure, primary fluid retaining means for retaining said fluid in said first receptacle, a second receptacle containing a fluid under pressure, secondary fluid retaining means for retaining said fluid in said second receptacle, delivery means into which the fluid from said first and said second receptacle is delivered when it is released, primary fluid actuated operating means for said primary retaining means to release the fluid from said first receptacle, secondary fluid actuated operating means for said secondary retaining means to release the fluid from said second receptacle, a direct fluid flow connection between said primary fluid actuated operating means and said first receptacle and a connection between said secondary fluid actuated operating means and said second receptacle, primary control means for said fluid flow connection to said primary operating means, fluid pressure actuated actuating means for said primary control means, and fluid pressure actuated secondary control means for said fluid flow connection to said secondary operating means, said secondary control means being in operative fluid flow connection with said primary control actuating means.

5. For use in a fluid medium dispensing system, the combination: a first receptacle containing a fluid under pressure, primary fluid retaining means for retaining said fluid in said first receptacle, a second receptacle containing a fluid under pressure, secondary fluid retaining means for retaining said fluid in said second receptacle, delivery means into which the fluid from said first and said second receptacle is delivered when it is released, primary fluid actuated operating means for said primary retaining means to release the fluid from said first receptacle, secondary fluid actuated operating means for said secondary retaining means to release the fluid from said second receptacle, a direct fluid flow connection between said primary operating means and said first receptacle and a connection between said secondary operating means and said second receptacle, primary control means for said fluid flow connection to said primary operating means, fluid pressure actuated actuating means for said primary control means, and fluid pressure actuated secondary control means for said fluid flow connection to said secondary operating means,

and individual manual control for the actuating means for both the primary and the secondary fluid connection control means, said secondary control means being in operative fluid flow connection with said primary control actuating means.

6. In combination: a primary receptacle containing a fluid under pressure, a secondary receptacle containing a fluid under pressure, delivery means into which the fluid from said primary and said secondary receptacle is delivered when it is released, primary fluid retaining means for retaining the fluid in said primary receptacle, primary fluid actuated operating means for said primary fluid retaining means to release the fluid from said primary receptacle, fluid actuated fluid release control means including secondary fluid retaining means adapted to release the fluid from said secondary receptacle, a fluid flow connection between said primary fluid actuated operating means and said fluid actuated fluid release control means, direct fluid flow connections respectively between said primary fluid actuated operating means and said primary receptacle and between said fluid actuated fluid release control means and said secondary receptacle, primary pilot valve means for said direct fluid flow connection of said primary receptacle, and actuating means for said primary pilot valve means, whereby said primary fluid actuated operating means and said fluid actuated fluid release control means are adapted to be actuated upon actuation of said primary pilot valve means.

7. In combination, a plurality of receptacles containing a fluid under pressure, fluid retaining means for retaining the fluid in each receptacle, delivery means into which the fluid from said receptacles is delivered when it is released, fluid actuated operating means for the retaining means of each receptacle to release the fluid therefrom, a direct fluid flow connection between each of said operating means and each receptacle, pilot valve means in each of said fluid flow connections, actuating means associated with each of said pilot valve means, and means operatively inter-connecting all of said pilot valve actuating means adapted to transmit an operating force for the operation of said pilot valve actuating means.

8. In combination, a plurality of receptacles containing a fluid under pressure, fluid retaining means for retaining the fluid in each receptacle, delivery means into which the fluid from said receptacles is delivered when it is released, fluid actuated operating means for the retaining means of each receptacle to release the fluid therefrom, a direct fluid flow connection between each of said operating means and each receptacle, pilot valve means in each of said fluid flow connections, actuating means associated with each of said pilot valve means, means operatively inter-connecting all of said pilot valve actuating means adapted to transmit an operating force for the operation of said pilot valve actuating means, and a releasable source of fluid pressure in operative connection with said last named means.

9. In combination, a plurality of receptacles containing a fluid under pressure, delivery means into which the fluid from said receptacles is delivered when it is released, fluid actuated fluid release control means including fluid retaining means for each of said receptacles to retain the fluid therein, a primary receptacle containing a fluid under pressure, primary fluid retaining means for retaining the fluid in said primary receptacle, fluid actuated operating means for said

primary retaining means, a direct fluid flow connection between said primary operating means and said primary receptacle, pilot valve means for said fluid flow connection, actuating means for said pilot valve means, and means operatively inter-connecting said primary operating means

and all of said fluid actuated fluid release control means, whereby all of said fluid retaining means are adapted to be operated to release the fluid in said containers upon an initial actuation of said 5 pilot valve means.

HARRY C. GRANT, JR.
